United States Patent Office.

DANIEL WERNER, OF ST. LOUIS, MISSOURI.

Letters Patent No. 82,908, dated October 6, 1868.

IMPROVEMENT IN BREECH-LOADING PISTOLS.

The Schedule referred to in these Letters Patent and making part of the same.

TO ALL WHOM IT MAY CONCERN:

Be it known that I, DANIEL WERNER, of the city and county of St. Louis, State of Missouri, have invented a new and useful Improved Combined Knife and Pistol, of which the following is a full, clear, and exact description, reference being had to the annexed drawing, making a part of this specification, in which—

Figure 1 represents a top view of my knife and pistol, with the blades of same open.

Figure 2 represents a side elevation of same, with a portion of the handle removed, showing the spiral spring and spindle.

Similar letters indicate like parts.

My invention consists in attaching to a knife-handle, A, figs. 1 and 2, one or more pistol-barrels, B B', fig. 1, and B, fig. 2, by means of two studs, c c', fig. 2, sliding on a spindle, d, screwed into the butt of the pistol. A spiral spring, e, fig. 2, is placed at the end of this spindle, next to the butt, and between it and the stud c'. A spring-catch, f, figs. 1 and 2, keeps the barrels of the pistol firmly against the breech-plate h, figs. 1 and 2. The lock of the pistol is in the butt, the triggers, K K', fig. 2, being beneath, and the hammers, m m', fig. 1, and m, fig. 2, above, as usual.

The knives open and shut in the usual way, and the lock is of the ordinary kind. The pistol is breech-loading.

By placing the thumb, as shown at p, fig. 2, the spring-catch being released, the spiral spring forces the barrels along the spindle, till they assume the position shown in fig. 2, when the cartridge may be inserted and the barrels pushed "home," the catch holding them as before.

This spring-catch is fastened at the muzzle of the pistol by a screw, s, fig. 1, but I do not confine myself to this particular arrangement of it, but claim it when applied in any equivalent manner.

The advantages of my invention consist in its compactness and simplicity, and the facility and rapidity with which the pistols may be loaded.

I do not intend to limit myself to the application of my method of breech-loading to the instrument described, but claim it when applied to any kind of fire-arm.

I do not claim to be the first inventor of a combined knife and pistol, nor of the method of loading pistols or other fire-arms at the breech, or of the use of a spring-catch to hold the barrel in place; but

What I do claim as my invention, and desire to secure by Letters Patent, is—

The barrels B, of the described pistol, provided with the catch f, located as shown and described, and having the studs c c', sliding upon the rod d, and operated in connection with the spring e, as described, when said barrels are combined with the stock and locks of an ordinary pistol, in the manner and for the purpose set forth.

DANIEL WERNER.
